United States Patent

Des. 239,411
Patented Mar. 30, 1976

239,411

PIANO

Winsor D. White, Jr., Chicago, Ill., and Dennis Barket,
Cincinnati, Ohio, assignors to D. H. Baldwin Company

Filed Aug. 26, 1974, Ser. No. 500,397

Term of patent 14 years

Int. Cl. D17—01

U.S. Cl. D56—9

FIG. 1

FIG. 2FIG. 3

FIG. 1 is a front, top and right side perspective view of a piano showing our new design;

FIG. 2 is a front elevational view; and

FIG. 3 is a right side elevational view, the left side being a mirror image thereof.

The rear of the piano is conventional.

We claim:

The ornamental design for a piano, substantially as shown and described.
